HANGER CLAMP

Andrew J. Hirt, Youngstown, Ohio, assignor to Hanger Supply Company, Youngstown, Ohio

Filed June 27, 1972, Ser. No. 266,534

Term of patent 14 years

Int. Cl. D8—08

U.S. Cl. D8—235

FIG. 1

FIG. 2

FIG. 3

FIG. 4

FIG. 5

FIG. 6

FIG. 7

FIG. 8

FIG. 1 is a perspective view of a first embodiment of the hanger clamp;

FIG. 2 is a side elevational view of the hanger clamp of FIG. 1;

FIG. 3 is a rear elevational view of the hanger clamp of FIG. 1;

FIG. 4 is a plan view of the hanger clamp of FIG. 1;

FIG. 5 is a perspective view of a second embodiment of the hanger clamp;

FIG. 6 is a side elevational view of the hanger clamp of FIG. 5;

FIG. 7 is a rear elevational view of the hanger clamp of FIG. 5; and

FIG. 8 is a plan view of the hanger clamp of FIG. 5.

I claim:

The ornamental design for a hanger clamp, substantially as shown and described.
